UNITED STATES PATENT OFFICE.

ZOUAVE S. RANDLEMAN, OF CARLISLE, IOWA, ASSIGNOR OF ONE-HALF TO ALBERT B. RANDLEMAN, OF CARLISLE, IOWA.

PAPER HOLDER AND DISPLAY RACK.

Application filed January 21, 1925. Serial No. 3,326.

The object of my invention is to provide a simple, durable and inexpensive paper holder and display rack, which is so constructed and arranged that newspapers, magazines and the like may be quickly and easily applied, and when so applied will be firmly supported in position and yet adapted to be readily removed.

More specifically it is the object of my invention to provide a paper holder or display rack having a number of yieldable supporting members which provide means for supporting a series of papers or magazines independently, all of the said independent supporting means being adapted to impart a gripping action to the papers supported therein by means of a single operating spring.

A further object is to provide a paper holder or display rack which is adapted to fold into a compact form and also capable of being unfolded to such position that it will stand alone in an upright position.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved device as used as a display stand.

Figure 2 is an end elevation of the same.

Figure 3 is an end elevation of a form adapted to be placed on a wall.

Figure 4 is an end elevation of a slightly modified form of my device.

My device comprises a supporting member 10 having an enlarged portion 11 at its lower end, said enlarged portion being provided with a cross member 12, said member 12 serving to provide a support to prevent the member 10 from rocking laterally when in an upright position.

45 I have provided two of the members 10 having their upper ends connected by a flexible member 13, so that the members 12 may be spaced apart a considerable distance in such a manner as to place the upright members 10 in oppositely inclined positions, so that the said upright members will stand upright. A flexible chain 14 is connected to one of the members 10 by means of an eyelet 15 and to the opposite member by means 50 of a hook 16. The said chain serves to pre-

vent the lower ends of the said upright members from spreading.

The member 11 has a screw 17 secured to each of its ends, said screws being designed to pivotally mount a substantially U-shaped gripping member 18, said member 18 being formed of wire having its free ends provided with loops 19 to receive the said screws 17. A second loop 20 is formed in each of the side members of the gripper 18 a slight distance above the loop 19. The upper or enclosed portion of the member 18 is provided with an outwardly bent portion 21.

Connected to the loops 20 of the member 18 is a similar gripping member 22 which is also provided with loops 23 designed to enter the loops 20 of the member 18, the member 22 being otherwise similar to the member 18. Any number of the grippers 22 may be provided, and they are connected together so that the loops 20 lie in a plane parallel with the body portion 10, while the side members of each of the grippers 22 lie substantially parallel to each other and in substantially vertical planes when the members 10 are set in the said inclined position.

The top one of the grippers 22 is provided with a yoke 24 which has its lower end pivotally connected with the loops 20, 85 said yoke lying adjacent to the outer face of the body 10 and extending upwardly and being connected to a spring 25, the upper end of which is placed over an upwardly and outwardly extending hook 26, said hook 90 being for the purpose of receiving and retaining bills and the like. A horizontally arranged spring 27 is placed immediately above the said hook 26 for preventing the bills or similar papers from being blown off. 95

By this construction it will be seen that tension on the spring 25 will have a tendency to yieldably support all of the gripping members in the position illustrated in Figure 1.

It will further be seen that any one of the grippers may be moved outwardly from its adjacent gripper, which outward movement will have a tendency to increase the tension on the spring 25.

By this construction, papers or paper sacks, envelopes, etc., may be placed between two of the gripping members and retained in said position by the gripping action imparted by the spring 25. It will be seen that 110

one of any number of these gripping members may be used, the spring 25 adapting itself to take care of the tension of all of them.

- 5 5. In Figure 3 I have shown the gripping members mounted on a single supporting board which may be rigidly secured to a wall if so desired, while the form shown in Figure 1 is adapted to be placed on the ground or floor surface, and constitutes a display rack or stand which is very convenient to be used in connection with the sale of newspapers, magazines and the like, as the stand may be easily and quickly removed 10 by simply unhooking the chain 14 from the hook 16 and then placing the yieldable member 13 over the operator's shoulder, making the device portable without removing the magazines from the stand.
- 15 10. In Figure 4 I have shown a slightly modified form which consists of a base 28 having a series of wooden strips 29 pivoted to each other by means of hinges 30, the lower one of said strips being pivoted to the lower end of the base 28, while the upper one of said strips 29 is hinged to a slide bar 31, the upper end of which is provided with a draw spring 32. The action of this device is similar 20 to the one above described.
- 20 15. By this arrangement it will be seen that I have provided a display rack and paper holder of simple, durable and inexpensive construction, which is adapted to receive a large variety of different shapes and sizes of 25 papers and magazines, which may be supported in independent groups, each of the groups being yieldably supported in position by means of a single spring, and which is readily adapted as a portable newspaper stand.

30 40. I claim as my invention:

1. A support comprising a bar having an enlarged portion at one end, a series of gripping members, each formed substantially of a U-shaped piece of wire, each of the parallel members of said wire having a loop, said

gripping members being mounted in an overlapping position with the free ends of one of said gripping members pivotally connected to the enlarged portion of said bar 50 with the free ends of the second one of said gripping members pivotally connected to the loop portions of the first gripping member, a yoke pivotally connected to the loop portions of the last one of said gripping members, and a contractile spring having one end connected to said yoke and its opposite end connected to said bar.

2. A support, a series of gripping members, each formed of substantially U-shaped 60 piece of wire, each of the parallel members of said wire having a loop between its closed portion and its free end, said gripping members being mounted in a partial overlapping position with the free ends of one of said gripping members pivotally connected to the corresponding loops of an adjacent gripping member, the first one of said gripping members having its free ends pivoted to said support, a yoke pivotally connecting the loop 70 portion of the last one of said gripping members, and a contractile spring having one end connected to said yoke and its opposite end connected to said support.

3. A vertical support, a series of gripping 75 members arranged in partially overlapping positions with their lower ends adjacent to said support and their body portions inclined upwardly and outwardly, the lower one of said gripping members having its 80 lower edge pivotally connected to said support, the lower edge of each of the other gripping members being pivotally connected to the gripping member beneath it and to a point between its upper and lower ends, and yieldable means having one end connected to the upper one of said gripping members and its opposite end connected to said support.

Des Moines, Iowa, January 12, 1925.

ZOUAVE S. RANDLEMAN.
